UNITED STATES PATENT OFFICE.

SHERMAN W. LADD, OF BEVERLY, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

No. 893,331.

Specification of Letters Patent.

Patented July 14, 1908.

Application filed April 18, 1901. Serial No. 55,728.

To all whom it may concern:

Be it known that I, SHERMAN W. LADD, of Beverly, county of Essex, and Commonwealth of Massachusetts, have invented certain Improvements in Lasting-Machines, of which the following, read in connection with the accompanying drawings, is a specification.

This invention relates to lasting machines and particularly to novel operating mechanism having provision for adjustment to vary the action of the machine upon the work.

The invention is shown as applied to the gripper operating mechanism and a very important feature of the invention consists in the combination with actuating mechanism that includes a yielding element and means for initially adjusting said mechanism to determine the tension of said element, of means that can be readily operated for changing the tension whereby the strain effected by the mechanism is modified. In the illustrated example in which the lasting machine grippers are connected with mechanism for uplifting them, there is a spring comprised in the operating mechanism and provision is made for initially compressing the spring to the normal tension required for the general run of the work in hand. There is also provided in accordance with this invention means which can be readily set by the operator as the work progresses for changing the tension of the updraw spring according to the requirements of a particular portion of the shoe being operated upon. To this end as shown a wedge is arranged for movement under the spring to compress or relax the spring as occasion may require and there is a connection from the wedge to a part that is within convenient reach of the operator for shifting the wedge. The wedge acts directly to change the tension of the spring, and there is provision for locking the wedge in its adjusted positions so that the spring will be maintained under the desired tension, throughout the movement imparted by it to the grippers and during repeated operations of the machine. These and other features of the invention, including certain combinations of parts and details of construction will be more fully explained in connection with the following description of the machine and will be definitely pointed out in the claims.

The invention is illustrated as applied to a lasting machine of the type shown in United States Letters Patent 584,744, and reference may be had to that patent for a full understanding of the portions of the machine which are not described in connection with this present invention.

Of the drawings Figure 1 is a side elevation of the machine. Fig. 2 is a perspective view showing parts comprised in this invention. Fig. 3 is a section on line 3 of Fig. 2. Figs. 4 and 5 are side elevations showing details connected with Fig. 2.

In operating the machine to which this invention relates, the grippers mechanism is first made to seize the edge of the upper and then move yieldingly upward to draw and strain the upper over the last. To this end the grippers carry a ball 4 (shown in dotted lines, Fig. 1) socketed for movement universally in the end of lever 2. Said lever carries a pin 6 which is journaled in the machine frame to permit vertical tilting movement of the lever by a force applied to its rear end. Such force is applied to the lever 2 from a cam (not shown) on the machine shaft D. To that end said cam is provided with a cam groove into which is projected a pin 8. Said pin is supported in the bar 10, and the cam groove is so fashioned as to impart, through this pin, to the bar 10 a longitudinal movement once in each direction, during a single revolution of the cam.

The bar 10 has screw threaded engagement with spindle 12. On said spindle is a sliding collar 14 having pivotal connection with the rear end of lever 2 and normally resting on the top of bar 10. Spindle 12 has screw threaded engagement with nut 16 and supports a loosely sliding collar 18. Between said nut 16 and collar 18 is a spiral spring 20 normally under tension. Interposed between the collar 18 and collar 14 is a wedge-slide 22 connected with which is a rod 24 extending forwardly to the grippers' end of lever 2 where it terminates in a handle 28 in position to be grasped by the workman while holding the shoe to the grippers.

It will be understood that an upward movement of the bar 10 lifts the rear end of lever 2 for positively lowering the grippers to the gripping position. A reverse or downward movement of bar 10 carries with it the spindle 12. In this movement spring 20 op-

erates as a connecting medium, transmitting movement of bar 10 to the lever 2, and reversely tilting lever 2 for uplifting the grippers to pull the upper until the tensional strain of the leather, developed by the uplifting grippers, exceeds the normal tension of spring 12. After this takes place, spring 12, contracting, acts as a yielding connecting medium, transmitting movement and force to the lever 2, so as to impart a yielding quality to the further uplifting movement of the grippers.

In the operation of the machine it has been found desirable to change the tension of spring 20 abruptly in order to get a stronger or less yielding pull on the upper, or vice versa, and the purpose of this invention is to provide for this change being made without impeding the operation of the machine.

20 The last, having the upper, its lining, etc., suitably applied thereon, with the inner-sole, on the bottom of said last, is held by the workman bottom upwardly against the rest 29 in position for the grippers to come forward and grip the edge of the upper. A single pair of grippers is employed which operates on a section of the upper at each complete operation of the machine. The shoe is moved by the workman step by step and 30 turned for bringing all parts of the upper, at different times, to the action of the grippers. If, during the lasting process, the workman, holding the shoe and observing the work, sees that a variation in the grippers' uplifting pull is desirable, he seizes the handle 28 and by it moves the slide 22 into position, relatively to the spindle 12, so as to contract or expand spring 20 as required for giving the pull desired. This obviously is accomplished by the workman at will and without discontinuing or in any way impeding the machine's continuous operation.

The movement of the wedge toward and from its operative position is made easier by 45 reason of the collar 18 being provided with anti-friction rollers 23 arranged to bear on the inclined face of the wedge, as shown. The wedge is slotted to embrace and be guided in its movements by the stem 12 of 50 the bar 10, as shown in Figs. 2 and 3. The wedge is provided at its upper end with shoulders 24^x which stand in front of the rollers 23 when the wedge is in its operative position for increasing the tension of the 55 spring 20. These shoulders serve as retaining means to hold the wedge in operative position. To release the wedge it is only necessary that it be pushed back by the workman 60 far enough to put the retaining shoulders 24^x under or back of the rollers 23, after which the spring 20, acting on the inclined face of the wedge, automatically forces it backwardly, or to the right in Fig. 5, until it reaches its inoperative position, shown in 65 Figs. 1 and 4, where the rollers rest on the

plane face of the slide and the spring 20 is under its normal tension to which it was initially adjusted by the adjusting nut 16. It will thus be seen that the machine is not only provided with the nut 16 for initially adjusting the tension of the spring through which the grippers are actuated, but that by the present improvement means is also provided, under the control of the workman and capable of being put into and out of operation at any time, for increasing the tension of the spring so that the grippers may be actuated with a greater force than that provided for by their initial adjustment. The wedge by which this adjustment is preferably effected 80 maintains the adjustment of the spring during repeated operations of the machine or until the wedge is again shifted. The shoulders 24^x serve to retain the wedge securely in its operative position until it is 85 positively released by the workman, after which the spring automatically returns the wedge to its inoperative position in the rear of the rollers, said rollers then resting on the plane portion of the slide at the foot of the 90 wedge.

Having thus described my invention, what I claim is:

1. A machine for working an upper over a last, comprising grippers for gripping the upper, actuating mechanism for the grippers including a yielding element, means for initially adjusting the actuating mechanism to determine the tension of said yielding element, and independent means under control 100 of the workman for directly changing the tension of said yielding element to modify the pulling tension of the grippers.

2. A machine for working an upper over a last, comprising grippers for gripping the upper, mechanism including a spring for actuating the grippers, means for initially adjusting the spring to determine its tension, and independent means under the control of the operator for directly adjusting the spring to 105 modify its tension and thereby determine the force with which the grippers are operated throughout the movement imparted to them by said actuating mechanism.

3. A machine for working an upper over a last comprising grippers for gripping the upper, yielding actuating mechanism for causing the grippers to pull the upper with yielding tension, means for initially adjusting said actuating mechanism to determine the 120 amount of said yielding tension, and independent means under control of the workman to change said mechanism at any time, thereby modifying the pulling tension of the grippers during the running of the machine, 125 said machine having provision for securing said last-mentioned means in adjusted position.

4. A machine for working an upper over a last comprising a lever, a grippers mech- 130

- anism applied to one end of the lever, a spring connection arranged to have engagement with the other end of said lever, an operating mechanism arranged to work 5 through said spring for causing said grippers to pull the upper, and means arranged to have engagement with said spring connection and extending to the grippers end of said lever for changing the tension of said 10 spring.
5. A machine for working an upper over a last comprising a pivoted lever, a grippers mechanism applied to the lever on one side of its pivotal point, a spring connection arranged to have engagement with said 15 lever on the other side of its pivotal point, an actuating mechanism operating through said spring connection for causing the grippers to pull the upper, and a device interposed between the actuating mechanism and said lever, and adapted for movement during the running of the machine, to change 20 the tension of said spring connection.
6. A machine for working an upper over 25 last comprising a pivoted lever, a grippers mechanism applied to the lever on one side of its pivotal point, a yielding mechanism arranged to operate on the lever on the opposite side of its pivotal point, mechanism 30 arranged to actuate the lever through said yielding mechanism for causing the grippers mechanism to pull the upper, and a wedge shaped device for changing the tension of said yielding mechanism, said device 35 having an extension to be operated from the grippers end of said lever.
7. A machine for working an upper over a last comprising grippers for gripping the upper, a cam having a constant throw, 40 mechanism between the cam and grippers for imparting to the latter by the former a pulling movement, said mechanism including a yielding medium, which is normally under tension, for giving a yielding quality 45 to the pulling strain of the grippers, means for initially adjusting said yielding medium and other means under control of the workman for changing the tension of said medium at will, thereby changing the amount of the 50 pulling tension of the grippers.
8. In a machine for working an upper over a last, a lever, a grippers mechanism connected to the lever at one side of its fulcrum, a spring connection applied to the 55 lever at the other side of its fulcrum, an operating mechanism acting through said spring connection for moving the lever, and an adjusting device under the control of the workman and located between the said 60 spring connection and the lever for varying the tension of the spring connection.
9. A machine for working an upper over a last, comprising a lever, a grippers mechanism connected to the lever at one side of its 65 fulcrum, a spring connection applied to the
- lever at the other side of its fulcrum, an operating mechanism acting through said spring connection for moving the lever, and an adjusting device under the control of the workman for varying the tension of the 70 spring, said machine having provision for automatically securing said device in adjusted position.
10. In a machine for working an upper over a last, a lever, a grippers mechanism connected to the lever at one side of its fulcrum, a spring, an operating mechanism acting through said spring at the other side of the fulcrum of the lever for moving the lever in the direction to uplift the grippers mechanism, and an adjusting device movable at the will of the workman toward and from operative position for increasing the tension of the 75 spring.
11. A machine for working an upper over 80 last, comprising a lever, a grippers mechanism connected to the lever at one side of its fulcrum, a spring, an operating mechanism acting through said spring at the other side of the fulcrum of the lever for moving the lever, and an adjusting device movable at the will of the workman toward and from operative position for increasing the tension of the 85 spring, said machine having provision for retaining the adjusting device in operative 90 position and for automatically moving said device into inoperative position when it is released.
12. In a machine for working an upper over 95 last, a lever, a grippers mechanism supported by one end of the lever, a yielding element applied to the other end of the lever, an operating mechanism acting through said yielding element for moving the lever, and a wedge arranged to be interposed between 100 said yielding element and the lever at the will of the workman for increasing the tension of the spring, whereby the grippers mechanism will be actuated with greater force in pulling 105 the upper.
13. In a machine for working an upper over 110 last, a lever, a grippers mechanism supported by one end of the lever, a yielding element applied to the other end of the lever, an operating mechanism acting through said yielding element for moving the lever, and a wedge arranged to be interposed between 115 said yielding element and the lever at the will of the workman for increasing the tension of the spring, and means for retaining the 120 wedge in its operative position.
14. In a machine for working an upper over 125 last, a pivoted lever, a grippers mechanism having connection with said lever, operating mechanism for said lever adapted to move the grippers mechanism positively in one direction, a yielding element in said operating mechanism whereby to move the grippers mechanism yieldingly in the opposite direction, means for initially adjusting 130

the tension of said yielding element, and other means under the control of the workman for varying the tension of said element.

15. A machine for working an upper over
5 a last, comprising grippers for gripping the upper, mechanism including a spring for actuating the grippers to pull the upper upwardly, means for determining the initial tension of the spring, and other manually controlled means for adjusting the spring to vary its tension, said latter means being constructed and arranged to maintain the spring under the desired tension during repeated operations of the machine.
- 10 16. A machine for working an upper over

a last, comprising grippers for gripping the upper, mechanism including a spring for actuating the grippers to pull the upper upwardly, a screw for initially setting the tension of the spring, and a wedge for adjusting 20 the spring to vary at the will of the operator the force with which the grippers will pull the upper.

Signed by me at Boston, Mass., this 12th day of April 1901.

SHERMAN W. LADD.
